DISPLAY APPARATUS

Paul J. Sanders, Maplewood, N. J.

Application September 28, 1935, Serial No. 42,552

16 Claims. (Cl. 40—104)

This invention relates to display apparatus and has particular reference to a display apparatus having means for successively swinging each of a series of display panels into display position, the 5 same being an improvement upon my previous United States Letters Patent, No. 1,960,553 and No. 1,967,843.

The present invention broadly comprehends a display apparatus including a driven flexible support upon which a series of display panels are swingably mounted for movement therewith and improved means moving in timed relation with the support for successively swinging the display panels about their respective pivotal connections with 15 said support as the same travel therewith.

The invention more specifically comprises in an apparatus of the indicated character, a rotary arm having improved panel engaging means for successively picking up display panels, elevating the same to an upstanding position and lowering 20 and releasing said panels.

Within the purview of the invention, the panel engaging means includes a pivotal catch which is gravitationally rockable as it is moved with the 25 rotary arm through top dead center to dispose the same in position to lower the display panel and to release the same adjacent the end of its downward movement and which catch is also engageable by means for automatically rocking the same on its pivotal engagement with the 30 rotating arm as it travels therewith through bottom dead center to move the catch from a position upon release of one display panel into position to pick up another display panel and to 35 elevate the same to an upstanding position.

The invention also contemplates in certain 40 of its forms, a pair of rotary arms moving in timed relation with the driven panel support and having panel engaging means arranged on the 45 ends thereof and means for moving the said panel engaging means as they travel with the arms through top dead center and bottom dead center, respectively, to dispose one of said panel engaging means in position to swing a display panel 50 engaged thereby from an upstanding position to a dependent position and in position to release the same and to dispose the other panel engaging means in position to engage with and elevate another display panel to upstanding position.

With the foregoing and other objects in view, 55 reference is made to the following specifications and accompanying drawings in which there is illustrated several embodiments of the invention, while the appended claims cover variations and

modifications thereof which fall within the scope of the invention.

In the drawings:

Fig. 1 is a perspective view of a display apparatus constructed in accordance with the invention and illustrating one of the panels being elevated and another being lowered. 5

Fig. 2 is a horizontal sectional view taken approximately on the line 2—2 of Fig. 3.

Fig. 3 is a vertical sectional view illustrating one 10 of the display panels in vertical upstanding position.

Fig. 4 is a similar view illustrating one of the display panels being lowered and another being elevated. 15

Fig. 5 is a similar view illustrating the position of parts immediately following the tripping of the lowermost catch and just prior to the picking up of the uppermost right hand display panel.

Fig. 6 is a sectional view through a display 20 apparatus illustrating a modified form of the invention and showing the position of parts just prior to the tripping of the lever for reversing the position of the display panel pick-up fingers.

Fig. 7 is a similar view showing the position 25 of parts immediately following the reversal of the fingers.

Fig. 8 is a vertical sectional view of a further 30 modification illustrating the position of parts as the pick-up mechanism releases the display panel which has been lowered to a depending position.

Fig. 9 is a similar view illustrating the position 35 of parts immediately following the engagement of the pick-up mechanism with a display panel and at the beginning of the elevating operation.

Referring to the drawings by characters of reference and particularly to the form of the invention illustrated in Figs. 1 to 5 inclusive, 14 designates a housing or cabinet having aligned window openings 15 and 16 in opposite walls 40 thereof for displaying therethrough in either an upstanding or a depending position a series of display panels 17. The mechanism for moving the display panels includes upper and lower rotary shafts 18 and 19 journaled in 45 bearing bars 20 in opposite side walls of the housing or cabinet and said shafts are provided respectively with longitudinally spaced pairs of sprockets 21—21 and 22—22 around which are trained endless flexible panel carriers such as the 50 sprocket chains 23—23. The display panels 17 include frames 24 which are removably pivoted to the sprocket chains 23 and are disposed therebetween in longitudinally spaced relation with reference thereto. As illustrated, the removable 55

pivoting of the frames 24 to the sprocket chains is accomplished by providing the chains with laterally and inwardly directed trunnions 25, the trunnions of one chain being in axial alignment 5 with those of the other and receiving thereover U-shaped bearings 26 closed at the inner ends and open at the outer ends to facilitate their engagement with the trunnions and their disengagement therefrom. In order to preclude lateral spreading 10 of the leads of the sprocket chains and consequent release of the display panel frames, a pair of vertically disposed channel shaped guides 27 are provided within the housing or cabinet 14, the same being supported by webs 28 which extend 15 laterally therefrom to the bearing bars 20 with which they are connected. The marginal flanges 29 of the guides 27 extend inwardly towards each other so that the sprocket chains 23 lie wholly within the confines thereof and are 20 covered and protected thereby.

In order to provide means adapted to move in timed relation with the panel supporting sprocket chains 23 for successively swinging the display panels 17 about their respective pivotal connections with the same, as they travel therewith, use is made of a pair of rotary arms 30 each of which is secured at its medial portion to the shaft 18 for rotation therewith. Each arm has pivoted thereto adjacent each outer end thereof on a 30 pivot 31, a rockable catch 32 and each catch includes a pair of inner and outer plates 33 and 34 lying on opposite sides of the arm and joined together by rivets 35 with spacing washers 36 therebetween located adjacent opposite corners of 35 the catch. In order to limit the rocking motion of the catches, the spacing washers 36 contact respectively with notched portions 37 in the opposite side edges of the arms. The catches are provided with outwardly divergent faces 38 which 40 constitute means for engaging with laterally projecting pins 39 on the panel frames 24 so as to successively pick up the display panels depending from one side of the device and elevate the same to an upstanding position, then lower the same 45 to a depending position on the other side of the device and finally release the panels successively when they reach said depending position on the opposite side of the device.

In Fig. 3 of the drawings, the uppermost panel 50 17 is disposed in an upright position at top dead center and the pin 39 is in a central position between the two outwardly divergent faces 38. As the shaft 18 rotates in a counterclockwise direction, as indicated by the arrows, the arms 30 55 turning therewith permit the uppermost catches to be gravitationally rocked with reference to the arms until the rearmost spacing washers 36 contact with the notched edges 37 of the arms thereby arresting further relative rocking motion of 60 these catches so that the leading faces 38 are in a position to support the display panel and lower the same from the position shown in Fig. 3 to the position shown in Fig. 4. Continued rotation of the shaft 18 in this direction lowers the panel 65 to the depending position on the left hand side of the device. After the panel has reached the depending position on the left hand side of the device, the catches 32 have the faces 38 so disposed with reference to the pins 39 that continued 70 rotation of the shaft disengages or releases the catches from the pins 39. In order to trip the catches as they reach bottom dead center so as to rock the same from the release position to the opposite position, as shown in Fig. 5, whereby the 75 divergent faces 38 will be disposed in a position

to receive the pins 39 of the uppermost depending panel on the opposite or right hand side of the device, fixed trip elements 40 are provided which, as shown, are in the form of laterally projecting webs on the guides 27 and the catches are provided with inwardly divergent arms 41 which are engaged by the trip elements as the catches move through bottom dead center. The following or rearmost faces 38 engage under the pins 39 and swing the panels upwardly on their pivotal connections with the sprocket chains as the chains move around the uppermost sprockets until the panel is elevated to the upstanding position at top dead center.

While the device has been illustrated and described as operating in a counter-clockwise direction, it is apparent that it may also be operated in the reverse or clockwise direction. Obviously the shaft 18 may be driven by motor or as illustrated by hand and as shown, a crank handle 42 extends through one side wall of the cabinet and through the bearing bar 20 and is provided with a sprocket 43 while the shaft 18 is provided with a sprocket 44, a sprocket chain 45 being trained around the sprockets 43 and 44. It will be observed that the display panels 17 which are in the depending position and not being acted upon by the catches on the arms 30 are supported at an angle and guided upwardly and downwardly by the engagement of the pins 39 with the flanges 29 of the guides 27.

In the form of the invention shown in Figs. 6 and 7, the means which is adapted to move in timed relation with the panel supporting sprocket chains 23 for successively swinging the display panels 17 about their respective pivotal connections with the same, as they travel therewith, consists of a pair of rotary arms 50 which correspond to the rotary arms 30, one only, however, being illustrated, in view of the fact that the other is a duplicate thereof. In this form, the arms 50 which are secured at their medial portions to the shaft 18 for rotation therewith are provided with a pair of superimposed straps 51 and 52 which are mounted for guided longitudinal sliding movement with reference to each other and with reference to the arm 50 by pin and slot connections 53 and 54, while the straps are centrally slotted as at 55 to clear the rotary shaft 18. The straps are respectively formed at each opposite end with an outwardly projecting finger, the fingers of one strap being located adjacent opposite side edges of the ends of said strap and the fingers of each strap being located at the opposite side edges of the other strap to provide in combination at each end of the arm 50 notches defined by the pairs of fingers of the two straps. As illustrated, the strap 51 which is located in superimposed relation on the arm 50 has its upper finger 56 in Fig. 6 of the drawings located adjacent the right hand edge 60 of the strap and its lower finger 57 located adjacent the left hand edge of the strap. The other strap 52 has its upper finger 58 located adjacent the left hand edge of the strap and its lower finger 59 located adjacent the right hand edge of the 65 strap. The straps are adapted to be moved relatively and with reference to the arm 50 so that the fingers located adjacent one side edge thereof are extended beyond the fingers located adjacent the other side edge of the arm and are adapted to 70 be elevated relatively in timed relation with the movement of the sprocket chains 23 to reverse their position in a manner and by a means which will be hereinafter described. As shown, the means consists of a pair of rock levers 60 and 61 75

which are fulcrumed on the pins 53 and overlie the strap 52. The opposite edges of the levers 60 and 61 are provided with diametrically disposed notches 62 and 63 which engage respectively with pins 64 and 65, the former projecting upwardly from the strap 52 and the latter projecting upwardly from the strap 51 and through slots 66 in the strap 52 to provide a clearance therefor. Obviously, upon swinging movement of the levers 10 60 in one direction, the straps 51 and 52 will be moved in opposite directions longitudinally and upon swinging movement of the levers 60 and 61 in the other direction, the straps will be shifted longitudinally in the other direction to reverse the 15 relative positions of the fingers 56, 57, 58, and 59. The levers are each provided with bifurcated inner ends, the furcations 67 of which diverge inwardly and are adapted for engagement with a stationary trip 68 which is the equivalent of the 20 trip element 40 in the previous form of the invention.

In use and operation of this form of the invention, assuming that the arm is being turned in the direction indicated by the arrow in Fig. 6, 25 although it is to be understood that the device may turn in either direction, the uppermost display panel 17 is shown just prior to the time it moves over top dead center while the lower left hand display panel 17 is shown just as it reaches 30 its release position and the lower right hand display panel is shown in a position just prior to being moved to a position to be elevated by the arm. In this position, the finger 56 is engaged behind the laterally projecting pin 39 of the panel 35 frame to raise the same, while the finger 59 of the strap 52 has just been released from engagement under the laterally projecting pin 39 of the lower left hand display panel 17 to lower the same to its release position. As shown in Fig. 6, the 40 left hand furcation 67 of the lower lever 61 is just starting to engage the trip 68. As the arm 50 continues to rotate in the counterclockwise direction, it will be apparent that the trip will swing both of the levers 60 and 61 until they assume the position shown in Fig. 7, thereby sliding 45 the strap 51 downwardly and the strap 52 upwardly, thus retracting the fingers 56 and 59 inwardly and projecting the fingers 57 and 58 outwardly so that upon continued movement of rotation of the arm in said direction the finger 58 will be engaged by the laterally projecting pin 39 for lowering the panel 17 which is just passing upper dead center, while the pin 57 will be disposed in a position to pick up the pin 39 of the lower right 50 hand display panel 17 which, due to the upward movement of the right hand lead of the sprocket chain 23, will be brought into a position to be engaged by the finger 57 to elevate the lower right hand display panel 17. The reversal of the position 55 of the levers 60 and 61 thereby disposes the right hand furcation of the upper lever 60 in a position to engage the trip when it moves to the lower position formerly occupied by the lower lever 61.

60 In the form of the invention illustrated in Figs. 3 and 9 of the drawings, the means which is adapted to move in timed relation with the panel supporting sprocket chains 23 for the purpose of successively swinging the display panels 17 about 65 their respective pivotal connections with the chains as they travel therewith, consists of a pair of radial arms 70 which correspond to the radial arms 30 in the first form of the invention, but only one being illustrated in the present 70 form. The arms 70 are secured at their medial

portions to the shaft 18 for rotation therewith and the arms are provided at each of their outer ends with a gripper mechanism for engagement with the laterally projecting pins 39 of the display panels so as to successively pick up the display panels depending from one side of the device, elevate the same to an upstanding position and then lower the same to a depending position on the other side of the device and finally release the panels successively when they reach said depending position on the opposite side of the device. 10

The pick-up mechanisms each includes a pair of fingers 71 pivotally connected together as at 15 72 and pivotally connected to links 73 respectively on axes 74 eccentric to the pivot 72 and on pivots 75 at opposite sides of the arm terminal. In order to provide means for moving the fingers towards and away from each other to pick up and release the laterally projecting pins 20 39 of the display panels, each gripper mechanism has connected therewith at the pivot 72, a rod 76 which extends inwardly therefrom and is slidably mounted on the arm. The inner ends of the rods 76 are each provided with an angularly 25 disposed terminal 77 constituting a cam follower which is engaged in the cam groove 78 of a fixed cam 79. The cam groove is provided with an offset lower portion 80 so that as the panels are lowered to a depending position, at the left side 30 of the device shown in Fig. 8, the rod 76 is moved outwardly to effect the opening of the gripper fingers 71 which are held in open position until the gripper mechanism passes lower dead center with the fingers located in a position to close upon 35 and engage with the laterally projecting pins 39 of the uppermost depending display panel 17 at the right hand side of the device. At this point, the terminals 77 of the rod move out of the offset portion 80 of the cam groove 78 to draw 40 the rod 76 inwardly for closing the gripper fingers 71 over the laterally projecting pins 39 to pick up said display panel and lift the same, as shown in Fig. 9. 45

What is claimed is:

1. In a display device, the combination of a conveyor, a rotary support therefor, a plurality of display panels pivotally carried by said conveyor, an arm movable with said support in an arcuate path concentric therewith, a rockable 50 catch pivoted to said arm and having outwardly divergent faces for successively engaging with and swinging said panels from a dependent position on one side to an upstanding position and to a dependent position on the opposite side, and 55 means on said catch engageable with a fixed means for rocking said catch to dispose the same in position to successively pick up the display panels.

2. In a display device, the combination of a conveyor, a rotary support therefor, a plurality of display panels pivotally carried by said conveyor, an arm movable in timed relation with said conveyor, means carried by said arm gravitationally rockable as the same is moved with 60 the arm through top dead center to dispose the same in position to lower the display panel engaged by said means and means engageable with said first mentioned means for rocking the same as it is moved with the arm through bottom dead 65 center to dispose said first mentioned means in position to pick up a display panel. 70

3. In a display device, the combination of a conveyor, a rotary support therefor, a plurality of display panels pivotally carried by said conveyor, 75

an arm movable in timed relation with said conveyor, means carried by said arm for successively engaging and swinging said panels about their respective pivotal engagements with said conveyor, and means engageable with said first mentioned means for disposing the first mentioned means in position to lower a panel from an upstanding position to a depending position and to release the same and pick up another display panel as the arm passes through top and bottom dead centers respectively.

4. In a display device, the combination of a conveyor, a rotary support therefor, a plurality of display panels pivotally carried by said conveyor, an arm movable in timed relation with said conveyor, a catch pivoted to said arm and having outwardly divergent faces for successively engaging with and swinging said panels about their respective pivotal connections with said conveyor as the conveyor moves around its support and having inwardly divergent faces engageable with a fixed means for rocking said catch to dispose the same in position to successively pick up the display panels.

5. In a display device, the combination of a conveyor, a rotary support therefor, a plurality of display panels pivotally carried by said conveyor, an arm movable in timed relation with said conveyor, a catch pivoted to said arm and having outwardly divergent faces for successively engaging with and swinging said panels about their respective pivotal connections with said conveyor as the conveyor moves around its support and having inwardly divergent faces engageable with a fixed means for rocking said catch as it passes through bottom dead center, to dispose the same in position to successively pick up the display panels.

6. In a display device, the combination of a conveyor, a rotary support therefor, a plurality of display panels pivotally carried by said conveyor, an arm movable in an arcuate path in timed relation with said conveyor, a rockable catch pivoted to said arm and having outwardly divergent faces for successively engaging with and swinging said panels from a dependent position on one side to an upstanding position and to a dependent position on the opposite side and having inwardly divergent faces engageable with a fixed means for rocking said catch to dispose the same in position to successively pick up the display panels.

7. In a display device, the combination of a conveyor, a rotary support therefor, a plurality of display panels pivotally carried by said conveyor, an arm movable in an arcuate path in timed relation with said conveyor, a rockable catch pivoted to said arm and having outwardly divergent faces for successively engaging with and swinging said panels from a dependent position on one side to an upstanding position and to a dependent position on the opposite side and having inwardly divergent faces engageable with a fixed means for rocking said catch as it passes through bottom dead center to dispose the outwardly divergent faces in position to successively pick up the display panels.

8. In a display device, the combination of a conveyor, a rotary support therefor, a plurality of display panels pivotally carried by said conveyor, an arm movable in an arcuate path in timed relation with said conveyor, a catch pivoted to said arm and having outwardly divergent faces for successively swinging said panels on their respective pivotal engagement with said conveyor,

said catch being gravitationally rockable on its pivotal engagement with said arm as the same is moved therewith through top dead center to dispose said faces in position to lower and release the display panels and said catch having inwardly divergent faces engageable with a fixed means as the catch is moved with the arm through bottom dead center to dispose the outwardly divergent faces in position to pick up a display panel.

9. In a display device, the combination of a conveyor, a rotary support therefor, a plurality of display panels pivotally carried by said conveyor, an arm movable in timed relation with said conveyor, means carried by said arm for successively engaging with and swinging said panels about their respective pivotal connections with said conveyor as the conveyor moves around its support and means engageable with said first named means for moving said first named means into position to engage with and pick up a display panel.

10. In a display device, the combination of a conveyor, a rotary support therefor, a plurality of display panels pivotally carried by said conveyor, an arm movable in timed relation with said conveyor, means carried by said arm for successively engaging with and swinging said panels about their respective pivotal connections with said conveyor as the conveyor moves around its support, and means engageable with a fixed means for moving said panel engaging means as it passes through bottom dead center into position to successively engage with and pick up the display panels.

11. In a display device, the combination of a conveyor, a rotary support therefor, a plurality of display panels pivotally carried by said conveyor, a pair of oppositely disposed rotary arms moving in timed relation with the conveyor, means carried by said arms respectively for successively engaging with and swinging said panels about their respective pivotal connections with said conveyor and means engageable with a fixed means for moving said panel engaging means as they travel with the arms through top and bottom dead centers respectively to dispose one of said panel engaging means in position to swing a display panel engaged thereby from an upstanding position to a dependent position and in position to release the same and to dispose the other of said panel engaging means into position to engage with and elevate another display panel to upstanding position.

12. In a display device, the combination of a conveyor, a rotary support therefor, a plurality of display panels pivotally carried by said conveyor, a pair of oppositely disposed rotary arms moving in timed relation with the conveyor, means carried by said arms respectively for successively engaging with and swinging said panels about their respective pivotal connections with said conveyor and means engageable with a fixed means for simultaneously moving said panel engaging means as they travel with the arms through top and bottom dead centers respectively to dispose one of said panel engaging means in position to swing a display panel engaged thereby from an upstanding position to a dependent position and in position to release the same and to dispose the other of said panel engaging means into position to engage with and elevate another display panel to upstanding position.

13. In a display device, the combination of a conveyor, a rotary support therefor, a plurality of display panels pivotally carried by said conveyor,

veyor, a pair of oppositely disposed rotary arms moving in timed relation with the conveyor, means carried by each of said arms for successively engaging with and swinging said panels about their respective pivotal connections with the conveyor, and means engageable with a fixed means for disposing said panel engaging means as they travel through bottom dead center in position to successively pick up and elevate the display panels.

14. In a display device, the combination of a conveyor, a rotary support therefor, a plurality of display panels pivotally carried by said conveyor, a rotary arm medially mounted to move in timed relation with the conveyor, a pair of superimposed straps mounted on said arm for guided longitudinal sliding movement with reference to each other and with reference to the arm, said straps each having an outwardly projecting finger at each of their ends, the fingers of one strap being located at the opposite side edges with reference to the fingers of the other strap, a rock lever pivoted to said arm adjacent each end thereof and having means engageable with said straps to shift the straps in opposite directions upon swinging of said rock levers to position said fingers to successively engage with and swing said panels about their respective pivotal connections with said conveyor, and means on said rock levers engageable with a fixed means for simultaneously shifting said straps in opposite directions when said rock levers respectively pass through bottom dead center to dispose a finger on one of said straps in position to lower one of said display panels and release the same at the bottom of its downward movement and to dispose one of the fingers on the opposite lever in position to engage with and elevate another display panel.

15. In a display device, the combination of a conveyor, a rotary support therefor, a plurality of display panels pivotally carried by said conveyor, a rotary arm medially mounted to rotate in timed relation with the conveyor, a pair of fingers adjacent the opposite edges of each of the ends of the arm, one finger of each arm being mounted for relative movement with reference to the opposite finger of each arm and with reference to the arm, and means operable upon rotation of the arm for shifting the fingers to successively pick up and swing said panels about their respective pivotal connections with said conveyor.

16. In a display device, the combination of a conveyor, a rotary support therefor, a plurality of display panels pivotally carried by said conveyor, a rotary arm medially mounted to rotate in timed relation with the conveyor, a fixed cam, a pair of oppositely disposed shiftable rods engaging said cam so as to shift said rods longitudinally of said rotary arm as the arm rotates, a pair of links pivoted to each of the outer ends of the arm, a pair of fingers pivoted to each of the outer ends of the rods, the fingers in each pair being pivoted together at the pivotal connection with the rods respectively and each finger being pivoted to the outer end of one of the links eccentric to the pivotal connection of the finger with the rod so that when the ends of the arm respectively pass through bottom dead center, the fingers of each pair swing outwardly and away from each other and in position to successively engage with and pick up the display panels and elevate the same.

PAUL J. SANDERS.
